COIN OPERATED UTILITY CONTROL OR
SIMILAR ARTICLE

Reuben E. Peot, Kahlots, Wash. 99335

Filed June 16, 1969, Ser. No. 17,709

Term of patent 14 years

Int. Cl. D20—01

U.S. Cl. D52—3

FIG. 1

FIG. 2

FIG. 1 is a left rear isometric view of the coin operated utility control or similar article embodying my new design; and

FIG. 2 is a right front isometric view as viewed from the side opposite FIG. 1 showing the coin operating mechanism thereof.

I claim:

Coin operated utility control or similar article, substantially as shown and described.
